ATTORNEY:

UNITED STATES PATENT OFFICE.

LESTER P. BARLOW, OF STAMFORD, CONNECTICUT.

ENGINE-COOLING SYSTEM.

Application filed August 5, 1926. Serial No. 127,257.

REISSUED

This invention relates to vapor cooling systems for internal combustion engines and more particularly those employed on automobiles, trucks, and other motor vehicles.

- 5 One object of my invention is to deliver to the jacket of the engine cylinders on starting the engine only enough liquid to fill the jacket to a predetermined level above the cylinders and then cease the flow of liquid to the jacket until the liquid therein reaches the boiling point, thereby allowing the engine to be warmed up quickly regardless of the outside atmospheric temperature in which the engine is started.
- 10 Another object of my invention is to automatically supply cooling liquid to the cylinder jacket in exact proportions to the amounts of liquid going off as steam from the surface of the liquid body in the jacket 20 from time to time during the steaming operation, and thus automatically maintain a substantially constant liquid level above the cylinders to prevent either flooding the jacket to stop the steaming operation or the 25 boiling away of the liquid body to overheat the cylinders.

A further object of my invention is to supply the cooling liquid to the cylinder jacket through a standpipe or chamber having a 30 by-pass at the height of the liquid level for the jacket, so as to regulate said level in the jacket yet allow for a continuous and uninterrupted circulation of liquid through the chamber to supply the jacket without 35 any of the excess liquids passing therethrough.

A further object of my invention is to so position the supply and reserve tank of the system that it may be readily reached 40 for filling.

A still further object of my invention is to locate this tank under the apron along the running-board at the side of the car and utilize a place not heretofore generally used 45 for this purpose.

The invention consists further in the matters hereinafter described and claimed.

In the accompanying drawings—

Fig. 1 is a side view (more or less diagrammatic) of an automotive power plant assembly equipped with a vapor cooling

system constructed in accordance with my invention;

Fig. 2 illustrates the supply and reserve tank of the system located beneath the apron 55 of the running-board at one side of the car;

Fig. 3 is a vertical sectional view taken on line 3—3 of Fig. 2; and

Fig. 4 illustrates a modified form of construction to be hereinafter described. 60

In Fig. 1, 1 indicates the cylinder block of an internal combustion engine, and 2 the head clamped on top of the block over the upper ends of the engine cylinders 3 therein, as usual in motor vehicle engine designs. 65 The block 1 is provided with the usual chamber 4 about the engine cylinders so as to receive the cooling liquids, as water, as heretofore, said chamber defining the water jacket about the cylinders, as usual. The head 2 70 has a vapor collecting space or steam dome 5 extending above the head and in direct communication at all times at its lower end with the upper end of the chamber 4 so as to receive the steam rising from the body 75 of the liquid in the chamber when brought to the boiling temperature from the heat of the explosions in the cylinders during the operation of the engine.

The dome 5 is connected with a header or 80 chamber 6 at the upper end of a cooler or condenser 7 by a conduit 8. The condenser may take the form of an automobile radiator with water tubes and air passages so as to fit in with the present automobile designs. 85 The lower portion of the condenser 7 is provided with a condensate collecting header or chamber 9, which is connected by a downwardly extending conduit 10 with a manifold 11 arranged below the condenser, as 90 shown in Fig. 1. The manifold 11 is connected by a conduit 12 with the intake of a pump 13, also located below the condenser 7 and driven from the engine in any desired manner. 95

At one side of the block 1 is a standpipe 14 opening at its lower end into the lower portion of the cylinder jacket through its liquid intake port 15. Through this standpipe liquid is supplied to the cylinder jacket 4 and maintained therein at a level a in the lower portion of the dome 5 and above the

cylinders, as shown in Fig. 1. The standpipe 14 extends upward from the port 15 to the water level *a* in the dome 5 and is connected at that level by an outlet or overflow pipe or conduit 16 with a supply tank or reservoir 17 located below the condenser 7, as shown. A supply conduit 18 connects the standpipe 14 with the discharge outlet of the pump 13, so that said pump when in operation delivers liquid to the standpipe and through the same supplies liquid to the jacket 4 to the level *a* therein.

The tank or reservoir 17 is connected with the manifold 11 on the intake side of the pump by a conduit 19 so as to supply make-up water to the system and permit the liquids to circulate through the standpipe 14 and its intake and overflow conduits 18 and 16 without passing through the cylinder jacket and the dome. The tank 17 has a capacity to contain all the liquid required for the system and sufficient in addition to constitute a reserve supply and thus compensate for natural losses through leakage and evaporation. Said tank 17 has a filling neck 20, the closure cap of which has a vent opening 21 to the atmosphere. Another vent 22 to the atmosphere is provided for the condenser 7 at its lower condensate collecting chamber 9, as shown. To balance the pressure in the dome 5 and in the regulating chamber 14, I provide a connection between them by a pipe 28, as shown in Fig. 1.

As shown in Fig. 1, the tubes 23, 23 of the condenser 7 are vertically disposed and connect the upper steam receiving chamber 6 with the lower condensate collecting chamber 9. These tubes are spaced apart so that air flowing through the condenser from front to rear will contact with the tubes to cool them and cause the steam passing downward through the tubes to be condensed and returned to liquid form to the system through the condensate collecting chamber 9. A fan 24 is located at the rear of the condenser 7 and is operated by the engine in the usual manner to draw air through the condenser for steam condensing purposes, as stated.

On first placing the system in operation, the tank or reservoir 17 is completely filled with cooling liquid through the neck 20 to the level indicated by the dotted line *b*. As the tank is so located as to extend above the pump 13 and manifold 11, these two elements as well as the conduits 12 and 19 and the portions of the conduits 10 and 18 below the level *b* are filled with liquid, thus priming all of the parts and not delaying their filling on starting the engine.

On first starting the motor or engine, the pump 13 draws liquid from the tank 17 and delivers it to the jacket, chamber 4 through the conduit 18 and standpipe 14. The pump fills the jacket chamber 4 to approximately

the level indicated by *a*, whereupon the flow to the jacket ceases, due to the fact that the overflow pipe 16 is connected with the upper end of the standpipe 14 at the height of the level *a*. The pump continues to operate and by the by-pass 16 circulates the excess liquid back through the tank without passing through the jacket, and thus making no change in the level *a*. From the fact that the flow of liquid to the jacket ceases when level *a* has been reached, the engine is allowed to warm up rapidly and bring the liquid in the jacket to the boiling point in a relatively short period of time and thus quickly raise the walls of the engine cylinders to the desired economical operating temperature, regardless of load conditions on the engine or the outside atmospheric temperature.

When the liquid in the jacket 4 reaches boiling or steaming temperature, steam rises from the level *a* of the liquid in the jacket and flows to the condenser 7 through the outlet conduit 8. The level *a* in the jacket is being constantly lowered to a slight extent by portions of the liquid body in the jackets going off as steam from the heat furnished by the explosions in the cylinders, thereby allowing the pump to constantly supply liquid to the jacket through the standpipe 14 to make up or compensate for the amounts going off as steam. As the by-pass or overflow conduit 16 opens into the standpipe 14 in the plane of the level *a* in the jacket, it follows that no more make-up liquid will be supplied to the jacket 4 than enough to compensate for the amounts going off as steam in the jacket. Thus the amounts of liquid supplied to the jacket from time to time during the boiling of the liquid in the jacket will be in direct proportion to the amounts of liquid going off as steam in the jacket. This is an important feature of my invention because not enough of the cooler liquid is supplied to the jacket at any time during the steaming operation to interfere with or hinder the same, thereby maintaining the cylinder walls of the engine at a substantially constant operating temperature regardless of load and atmospheric temperature conditions. While considerably more amounts of the liquid about the engine cylinders will be converted into steam from time to time during the operation of the engine under heavier loads than under lighter loads, yet the amounts of cooler liquid supplied to the jacket under a heavier load from time to time will not be sufficient to hinder the steaming action in the jacket as to materially reduce the operating temperature of the cylinder walls.

Steam entering the chamber 6 at the top of the condenser 7 will be forced downward through the tubes 23, 23 by the pressure in the dome 5. The tubes being cooled by the

circulation of air against them, will cause the steam therein to be condensed therein, the condensate flowing by gravity to the lower chamber 9. From there, the condensate liquid will flow downward into the manifold 11 through the conduit 10, and thus be collected to be taken up by the pump 13 and be returned to the system for resupplying the jacket with liquid in proportion to the amounts going off as steam therein.

I prefer, when my improved system is used with automobiles, to place the supply and reserve tank 17 in a position where it may be readily reached for filling through the neck 20, from the exterior of the car. In Figs. 2 and 3 of the drawings, I have shown the tank 17 located in the space between the apron 25 and the running-board 26 at one side of the car and the adjacent side member 27 of the frame or chassis of the machine. The tank 17 has its filling neck 20 extended upward through an opening in the apron 25 so that it may be reached for filling the tank from the outside of the car. To avoid the use of unduly long conduits 16 and 19 between the tank and the associated parts of the system I prefer to position the tank toward the front end of the car, as shown in Fig. 2.

While I have shown in Fig. 1 the overflow conduit 16 as connecting the standpipe 14 directly with the tank 17, I may arrange this overflow pipe 16 so as to connect the upper end of the standpipe at the water level *a* with the intake side of the pump 13, as shown in Fig. 4. This arrangement shortens the distance of flow from the standpipe 14 to the intake of the pump, which may be desired in some installations. Moreover, by this arrangement the return flow from the standpipe 14 to the pump is not through the supply tank 17 to disturb or heat the same as with the assembly shown in Fig. 1.

While I have shown and described the standpipe 14 as made separate from the cylinder block 1, it could be formed integral with said block, as by making a suitable passage or alcove therein. In either case, it would serve as a chamber to regulate the level of the liquid body about the cylinders and also enable the liquid to be supplied to said body in direct proportion to the amounts going off as steam therefrom during the steaming operation. After the system has been initially filled with liquid through the tank 17, no further filling is required over relatively long periods of time, as practically all steam generated in the jacket is condensed and returned to the system. On stopping the motor steam will continue until the temperature of the cylinder walls drops below the boiling point of the liquid used. The pump 13 being idle, no liquid will be supplied to the jacket to make-up for the amounts going off as steam.

The level *a* will naturally lower, it being raised, however, to the height required on the first starting of the engine.

The details of construction and arrangement of parts may be variously changed and modified without departing from the spirit and scope of my invention.

I claim as my invention:

1. In an internal combustion engine vapor cooling system which is open continuously to the atmosphere and which operates at all times at atmospheric pressure, the combination with a cylinder jacket having a steam space above the same, of means providing a circuit whereby a cooling liquid may be continuously circulated without passing through said jacket, and means included in said circuit and connected with said jacket whereby a predetermined liquid level may be maintained in the jacket by supplying liquid thereto from the circuit in direct proportion to the amounts going off as steam in the jacket.

2. In an internal combustion engine vapor cooling system which is open continuously to the atmosphere and which operates at all times at atmospheric pressure, the combination with a cylinder jacket having a steam space above the same, of means providing a circuit whereby a cooling liquid may be continuously circulated without passing through said jacket, said circuit including a liquid level regulating chamber for the jacket and through which the circuit enters the jacket, said chamber having its outlet to the circuit at the height of the liquid level for the jacket in order to maintain such level by supplying liquid to the jacket from the circuit in direct proportion to the amounts going off as steam in the jacket.

3. In an internal combustion engine vapor cooling system which is open continuously to the atmosphere and which operates at all times at atmospheric pressure, the combination with a cylinder jacket having a steam space above the same, of means providing a circuit whereby a cooling liquid may be continuously circulated without passing through said jacket, said circuit including a liquid level regulating chamber for the jacket and through which the circuit enters the jacket, said chamber having its outlet to the circuit at the height of the liquid level for the jacket in order to maintain such level by supplying liquid to the jacket from the circuit in direct proportion to the amounts going off as steam in the jacket, and a supply and reserve reservoir in constant communication with said circuit.

4. In an internal combustion engine vapor cooling system which is open continuously to the atmosphere and which operates at all times at atmospheric pressure, the combination with a cylinder jacket having a steam space above the same, of means providing

a circuit whereby a cooling liquid may be continuously circulated without passing through said jacket, a liquid level regulating chamber for the jacket and a forcing pump 5 in said circuit with the latter entering the jacket through said chamber, a reservoir in the circuit, said chamber having its inlet and outlets connected with the discharge of the pump and with the reservoir, respectively, 10 the outlet of said chamber being at the height of the liquid level for the jacket in order to maintain said level by supplying liquid to the jacket from the circuit in direct proportion to the amounts passing off as 15 steam in the jacket.

5. In an internal combustion engine vapor cooling system which is open continuously to the atmosphere and which operates at all times at atmospheric pressure, the combination 20 with a cylinder jacket having a steam space above the same, of means providing a circuit whereby a cooling liquid may be continuously circulated without passing through the jacket, said circuit including a liquid 25 level regulating chamber for the jacket and connected with the intake thereof, said chamber having its outlet to the circuit at the height of the liquid level for the jacket in order to maintain such level by supplying 30 liquid to the jacket from the circuit in direct proportion to the amounts going off as steam in the jacket, and a condenser connected at its upper end with the steam space and at its lower end with the return side only of said 35 circuit for supplying condensate thereto.

6. In an internal combustion engine vapor cooling system which is open continuously to the atmosphere and which operates at all times at atmospheric pressure, the combination 40 with a cylinder jacket having a steam space above the same, of means providing a circuit whereby a cooling liquid may be continuously circulated without passing through said jacket, said circuit including a standpipe 45 arranged outside of the jacket and through which standpipe the circuit enters the jacket for supplying liquid thereto, said standpipe having inlet and outlet openings included in the circuit with the outlet opening at the height of the liquid level for the 50 jacket.

7. In an internal combustion engine vapor cooling system which is open continuously to the atmosphere and which operates at all 55 times at atmospheric pressure, the combination with a cylinder jacket having a steam space above the same, of means providing a circuit whereby a cooling liquid may be continuously circulated without passing through said jacket, said circuit including a standpipe arranged outside of the jacket and connected at its lower end with the intake of the jacket for supplying liquid thereto, 60 said standpipe having inlet and outlet openings included in the circuit with the outlet 65

opening at the height of the liquid level for the jacket, and a condenser connected at its upper end with the steam space and at its lower end with the return side only of the circuit for supplying condensate thereto. 70

8. In an internal combustion engine vapor cooling system which is open continuously to the atmosphere and which operates at all times at atmospheric pressure, the combination with a cylinder jacket having a steam space above the same, of means providing a circuit whereby a cooling liquid may be continuously circulated without passing through the jacket, said circuit including a chamber connected with the intake of the 75 jacket for supplying liquid thereto, said chamber having its outlet to the circuit at the height of the liquid level for the jacket in order to maintain such level by supplying liquid to the jacket from the circuit in direct 80 proportion to the amounts going off as steam in the jacket, a condenser connected at its upper end with the steam space and at its lower end with the return side only of said circuit for supplying condensate thereto, and 85 a pressure balancing connection between the chamber and said steam space.

9. In a cooling system for internal combustion engines, the combination with a cylinder jacket, of means providing a circuit whereby a cooling liquid is circulated without passing through said jacket, means to maintain the cooling liquid at a predetermined level in the jacket, and a vent for said system, said vent being continuously open to the atmosphere whereby the system operates at all times at atmospheric pressure. 90

10. In an internal combustion engine vapor cooling system which is open continuously to the atmosphere and which operates at all times at atmospheric pressure, the combination with a cylinder jacket having a steam space above the same, of means providing a circuit whereby cooling liquids may be continuously circulated without passing through said jacket, said circuit including a chamber connected with the intake of the jacket for supplying liquids thereto, and a supply and reserve reservoir connected with said circuit for supplying liquids thereto, 105 said chamber having its outlet for liquids connected with the reservoir and disposed at the height of the liquid level to be maintained in the jacket. 110

11. In an internal combustion engine vapor cooling system which is open continuously to the atmosphere and which operates at all times at atmospheric pressure, the combination with a cylinder jacket having a steam space above the same, of means providing a circuit whereby cooling liquids may be continuously circulated without passing through said jacket, said circuit including a chamber connected with the intake of the jacket for supplying liquids thereto, a sup- 120 125 130

- ply and reserve reservoir connected with the circuit for supplying liquids thereto, and a condenser connected with said steam space and the return side, respectively, of the circuit for supplying condensate thereto, said chamber having its outlet for liquids connected with the reservoir and disposed at the height of the liquid level to be maintained in the jacket.
- 10 12. In an internal combustion engine vapor cooling system which is open continuously to the atmosphere and operating at all
- 5 times at atmospheric pressure, the combination with a cylinder jacket, of means for supplying cooling liquid to said jacket comprising means for circulating the cooling liquid without passing through said jacket, and means for so controlling the admission of liquid from said circuit to the jacket as to maintain the cooling liquid in the jacket 20 at a predetermined level.

In testimony whereof I affix my signature this 2nd day of August, 1926.

LESTER P. BARLOW.
